KILN STRUCTURE

James T. Robson, Richmond Heights, Edward H. Watkins, Cleveland, and Edwin G. Zimmerman, Avon, Ohio, assignors to Ferro Enamel Corporation, Cleveland, Ohio, a corporation of Ohio

Application March 10, 1941, Serial No. 382,536

7 Claims. (Cl. 25—142)

This invention relates to air moving means for kilns or the like and more particularly to improved means for preheating and directing air to the burners of a tunnel kiln of the type used for firing ceramic ware.

In kilns and other heating structures where air or other gases are caused to circulate and move in predetermined manner through the apparatus it is frequently desirable to move air or gas under pressure at very high temperatures such as 1500° F. to 2400° F. So called high temperature fans or blowers have been employed to handle gas not over 1600° F. but because they must withstand the high temperatures at which they operate they involve difficult lubrication and upkeep problems and are therefore expensive to install and maintain. Such fans cannot successfully handle air as hot as 2400° F. The present invention provides a simple means for moving highly heated gases which completely avoids the necessity for high temperature fan equipment, which will handle much higher temperatures than previously proposed apparatus, is of low first cost and substantially completely eliminates maintenance expense.

In this specification our invention is described as applied to supply hot air to kiln burners but other applications where very hot gases are to be moved will occur to those skilled in the art and the present description is to be considered illustrative rather than limiting.

Tunnel kilns, in which the ware passes through the kiln on cars or other conveyors, are commonly heated by gas and oil burners suitably located in the firing section of the kiln. These burners are supplied with fuel through proper valves and the necessary air for combustion may, in some cases, be partially mixed with the fuel and partially discharged around the burner nozzle at the point of combustion. In such operation the air which is mixed with the fuel and introduced directly through the burner nozzles is termed primary air while the air which is introduced around the burner nozzle is termed secondary air. It will be understood that in other cases the primary air is omitted entirely and all of the air for combustion is introduced around the burner nozzle.

Various means have been employed for pre-heating the air supplied to a burner to increase the efficiency of combustion, and it is an object of the present invention to provide an improved means for supplying pre-heated air to a burner which means will automatically maintain a substantially constant temperature of the supplied

air during changes in the quantity of such air supply.

Other objects of our invention include: the provision of a simple and effective means for moving highly heated gases; the provision of a kiln structure in which highly heated atmosphere from within the kiln is withdrawn from the tunnel and mingled with air from outside to raise the temperature of the mixed air to the desired degree for most efficient combustion at the burner, and the mixed air supplied to the kiln burners under pressure; the provision of proportional mixing means for supplying air for combustion to the burners of a kiln or other type of furnace; and the provision of an exceedingly simple and entirely automatic means for supplying air at substantially constant temperature to a burner over a wide range of quantity of air flow; the provision of simple and economical means for supplying air to a burner at elevated temperature and under pressure, thus insuring a uniform feed of air to the burner at all times and eliminating flashing during changes of the burner setting to vary the heat input to the furnace; and the provision of automatic means for maintaining a proper air supply to a burner during variations of the fuel supply.

The above and other objects of our invention will appear from the following description of one embodiment thereof, reference being had to the accompanying drawings, in which—

Figure 1 is a fragmentary somewhat diagrammatic side elevational view of a kiln equipped with our proportional mixing combustion air feeding apparatus.

Figure 2 is a transverse cross sectional view through the kiln shown in Figure 1 taken substantially on line 2—2 of Figure 1.

Figure 3 is a longitudinal vertical sectional view through the refractory proportional inspirating mixers on one side of the kiln structure shown in Figure 1 taken substantially on line 3—3 of Figure 1.

Figure 4 is a transverse cross sectional view taken on line 4—4 of Figure 1.

Figure 5 is a transverse cross sectional view taken on line 5—5 of Figure 1.

In Figure 1 a tunnel kiln is indicated generally at 1 and may be of any suitable and well known form. The ware progresses through the kiln on cars 1a in the direction of the arrow (Fig. 1) and a pre-heating section (not shown) may precede the firing section F and cooling section C, illustrated in Figure 1. A plurality of burners are located in the firing section, there being four

on each side in the illustrated embodiment. The burners 2 and 3 may be considered as one set and burners 4, 5 and 6 and similarly located burners on the opposite side of the kiln may be considered as another set. The supply of pre-heated air to burners 2 and 3 is separate from the supply for the other burners of the kiln and it will be understood that any suitable number and arrangement of burners may be employed to achieve the desired heating effect in the kiln.

In the cooling portion C of the kiln there are cooling panels 7 and 8 of relative thin refractory material. When the ware reaches these panels in its progress through the kiln it is cooled and heat is transmitted through these panels from the ware to the air which flows behind the panels, as will be later described.

The roof of the cooling section of the kiln has spaced refractory walls 8 and 9. Longitudinal vertical walls 10, 11 and 12 divide the space between the walls 8 and 9 into four ducts or passages 13, 14, 15 and 16. A blower fan 17, driven by any suitable means (not shown), provides a source of supply of outside air under pressure and forces air through the pipe 18 into each of the passages 13, 14, 15 and 16 and as this air travels over the top of the cooling section of the kiln it is heated to a certain degree. Suitable damper valves 13', 14', 15' and 16' are disposed in ducts 13, 14, 15 and 16 respectively. Preferably dampers 13' and 16' are connected to operate together and dampers 14' and 15' are also operable as a unit. The two outside ducts 13 and 16 terminate at 19 (Fig. 1) and downwardly extending passages 20 and 21 carry air from the passages 13 and 16 respectively down past the cooling panels 7 and 8 into longitudinally extending ducts 22 and 23, which extend along the bottom part of the kiln structure on either side thereof.

In Figure 3 our inspiring mixer is illustrated disposed in the duct 22. This hot gas moving device comprises a refractory block 24 having a flared hole 24^a extending therethrough to form a nozzle outlet for duct 22. The block 24 is spaced from the refractory Venturi block 25 and a chamber 26 is formed around the spaced gap between the nozzle block 24 and the Venturi block 25. A passage 27 connects the opening 28 to the proportional mixer. The relief port opening 28 leads directly into the interior of the kiln tunnel and when air is discharged through the duct 22 by the fan 17 it passes through the nozzle 24 into the Venturi element 25 drawing in with it hot air from the interior of the kiln through passages 26, 27 and 28. As the air from the kiln tunnel is very hot it will raise the temperature of the air which passes on through the duct 22^a to the burner 2 to the desired temperature. When the supply of fuel, or fuel and air, which is conducted to the burner 2 through pipe 2^a and control valve 2^b is increased, additional air should also be supplied through the duct 22^a and this is accomplished by opening the damper 13' in the duct 13 which leads to duct 22. The resulting increased flow of air through the duct 22 causes a proportionally increased amount of highly heated air to be drawn into the venturi 25 and mixed with the air from the duct 22.

By properly proportioning and spacing the mixer parts and openings air which is discharged through the duct 22^a to the burner 2 will be maintained at a substantially constant temperature over a very considerable range of flow and

thus, regardless of the load imposed upon the burner 2, a proper supply of air at the desired temperature may be obtained. Interconnections are preferably provided between the control valve 2^b for supplying fuel to the burner 2 and the valves or dampers 13' which controls the flow of air through the duct 22 and thus when the fuel supply is increased the flow of air to the burner will automatically be increased.

These interconnecting means may be either electrical or mechanical. In Figure 1 electrical valve and damper actuating devices are diagrammatically illustrated. Valve 2^b is operated by a lever 2^c connected to and actuated by the operating unit 2^d which may be of either the solenoid or motor type. Damper 13' is operated by a lever 13'' actuated by an operating unit 13'''.

The control unit A is connected to the line L and to the operating units 2^d and 13''' by suitable wiring W and W' and movement of the lever A' in the proper direction will open or close the valve 2^b and damper 13' simultaneously. The details of the control devices are not shown as they may be of any suitable and well known type.

The burner 3 (Fig. 5) is supplied with air through the duct 23^a which is connected to the duct 23 having a similar proportional mixing device installed directly opposite the elements 24 and 25. This proportional mixer (which is not seen in the drawings) withdraws air from the kiln tunnel in the manner described above in reference to the proportional mixer 24-25. In like manner the two center ducts 14 and 15 are connected to the ducts 29 and 30 which lead to proportional mixture devices of the same form as previously described and one of which is illustrated at 31 and 32 in Figure 3. A passage 34 connects the inlet to the venturi 32 to the opening 28 and thus, when air is forced through the duct 29 and the jet outlet 31 thereof, air will be drawn into the Venturi member 32 from the kiln tunnel through the openings 28 and 34. The hot air from the tunnel is mixed with the cooler air and carried on through the extension of the duct 29 to vertical passages 35 and 36. Passage 35 supplies air to burners 4 and 5 and, in similar manner, passage 36 supplies heated air to the burner 6.

It will be understood that the passage 30 (Figure 2) includes a similar proportional mixer (not shown) and supplies air at the proper temperature to the burners corresponding to, and located on the opposite side of the kiln from, burners 4, 5 and 6. In like manner suitable dampers 14' and 15' are inserted in the conduits 14 and 15 to control the flow of air therethrough and these conduits are preferably connected to operating means, similar to that described above for burner 2, whereby the flow of air is increased when the supply of fuel to the burners is increased.

By withdrawing air from the tunnel and mixing it with air which has been pre-heated to a certain degree by passage over the cooling plates 7 and 8 and through the ducts 13, 14, 15 and 16, a material heat economy is obtained and highly heated air is delivered to the burners at the proper temperature at all times regardless of variations in the demand of the burners for air. By positively feeding the air to the burners under pressure at a substantially constant and proper temperature uniform and efficient burner operation is obtained.

It will be understood that although the draw-

ings illustrate a single supply of air to the burners, additional air may be introduced with the fuel through the pipes which supply the fuel to the burners. Also, it will be understood that suitable valves and dampers will be employed to control the fuel and air supply to each burner or group of burners, although, for simplicity, only the control for burner 2 has been specifically shown and described herein. By inspirating heated air from the tunnel, mixing it with fresh air and forcing this air positively into the ducts feeding the burners, and by automatically controlling the proportion of outside air to air from the tunnel so that a substantially constant temperature of the air to the burners is maintained, control of the temperature within the kiln structure is greatly improved and simplified. In actual practice of the present invention in ceramic kilns the air from fan 17 is heated to about 800° F. to 1000° F. in the ducts leading to the refractory inspirators and is brought up to about 1400° F. to 1500° F. by the addition of hot air from the tunnel. In a typical installation about 70% of the air supplied to the burners is drawn from the tunnel and it will be seen that by making possible the withdrawal and handling of the very high temperature furnace atmosphere and by automatically maintaining the proper proportional mixing of air from two sources an adequate supply of air at the desired high temperature is assured. The interconnection of the fuel and air control valves, combined with the proportional mixer for maintaining proper air temperature, results in efficient and trouble free burner operation at all times.

Although we have described the illustrated embodiment of our invention in considerable detail, it will be understood by those skilled in the art that numerous variations and modifications may be made in the specific form and arrangement of the parts and we do not, therefore, wish to be limited to the particular embodiment herein shown and described but claim for our invention all forms thereof coming within the scope of the appended claims.

We claim:

1. In a kiln structure, apparatus for withdrawing highly heated gas from a part of said kiln structure comprising, a duct disposed within a kiln wall, means for supplying air under pressure to said duct, a refractory nozzle member within said kiln wall and forming an outlet from said duct, a refractory Venturi member within said kiln wall and spaced from but having its inlet end adjacent to the outlet of said nozzle, said kiln wall having a chamber adjacent the space between the outlet from said nozzle and inlet to said venturi, and means for conducting gas from said part of said kiln to said chamber.

2. In a kiln structure having a burner, apparatus for supplying fuel and heated gas to said burner comprising, a pipe for conducting fuel to said burner, means for controlling the flow of fuel through said pipe, a duct in a kiln wall, means for moving outside air through said duct, said duct having a nozzle outlet within said kiln wall, a Venturi inspirating member within said kiln wall adjacent said nozzle outlet, means for conducting hot air from within the kiln to said inspirating member, means for conducting a mixture of outside and kiln air from said inspirating member to said burner, and interconnected operating means for said fuel control and outside air control means whereby, when the supply of fuel to the burner is increased, the flow of out-

side air through said duct will be increased and the supply of heated air to the burner correspondingly increased.

3. In a tunnel kiln of the type described having a firing section and a cooling section, a burner positioned to supply heat to said firing section, a pipe for supplying fuel to said burner, valve means for controlling the flow of fuel to said burner, a duct in heat exchange relation to said cooling section, blower means for moving air into said duct, valve means for controlling the flow of air through said duct, a refractory nozzle forming a discharge outlet for said duct, a refractory Venturi member having inlet and outlet openings, said inlet being positioned to receive air from said nozzle, a passage extending from adjacent said Venturi inlet into the kiln tunnel, a passage extending from said Venturi outlet to said burner, and interconnecting means for simultaneously opening and closing said fuel and air control valves.

4. In a kiln structure having a ware chamber defined by walls, an air duct in one of said walls, a refractory inspirator in said air duct within said wall, a passage from said inspirator through said wall into said ware chamber, and means for moving air through said air duct and refractory inspirator whereby hot air from said ware chamber will be withdrawn through said inspirator while being maintained within the confines of said kiln walls.

5. In a kiln structure having a ware chamber defined by walls, an air duct in one of said walls, a refractory inspirator in said air duct within said wall, a passage from said inspirator through said wall into said ware chamber, means for moving air through said air duct and refractory inspirator whereby hot air from said ware chamber will be withdrawn through said inspirator while being maintained within the confines of said kiln walls, a burner positioned to heat said ware chamber, and a passage within said wall for conducting the air from said air duct and said ware chamber to said burner.

6. In a kiln structure, a tunnel having a roof and side walls and including a firing section and a cooling section, a passage in said roof over said cooling section, damper means for controlling the flow of air through said passage, means for forcing air through said passage, a cooling panel in a side wall of said cooling section, duct means in said side wall for conducting air from said roof passage over said cooling panel, said duct means continuing within said side wall toward said firing zone, a refractory nozzle within said wall at the end of said duct means, a refractory Venturi member within said side wall and having its inlet adjacent the outlet of said nozzle, said wall having a chamber around said nozzle and venturi whereby a refractory inspirator is formed, duct means from said chamber into said tunnel, a burner directed to supply heat to said firing section, and duct means in said wall for conducting mixed fresh air and tunnel atmosphere from said venturi to said burner.

7. In a kiln structure, a tunnel having a roof and side walls and including a firing section and a cooling section, a passage in said roof over said cooling section, damper means for controlling the flow of air through said passage, means for forcing air through said passage, a cooling panel in a side wall of said cooling section, duct means in said side wall for conducting air from said roof passage over said cooling panel, said duct means continuing within said side wall toward said fir-

ing zone, a refractory nozzle within said wall at the end of said duct means, a refractory Venturi member within said side wall and having its inlet adjacent the outlet of said nozzle, said wall having a chamber around said nozzle and venturi whereby a refractory inspirator is formed, duct means from said chamber into said tunnel, a burner directed to supply heat to said firing section, duct means in said wall for conducting

5 mixed fresh air and tunnel atmosphere from said venturi to said burner, valve means for controlling the flow of fuel to said burner, and interconnected operating means for said valve and damper whereby opening of said fuel valve means will increase said damper opening.
